UNITED STATES PATENT OFFICE

2,545,741

ESCALATOR HAND RAIL

Walter F. Masek, Coffeyville, Kans., assignor to
Multiscope, Inc., Coffeyville, Kans., a corpora-
tion of Kansas

Application April 18, 1946, Serial No. 663,223

3 Claims. (Cl. 198—16)

1

This invention relates generally to escalators and particularly to a hand rail therefor.

The object of the invention, generally stated, is to provide a hand rail for escalators, which may be economically constructed, easily repaired, and is withal adaptable to various shapes, contours, and applications of escalators.

Other objects will become apparent to those skilled in the art when the following description is read in connection with the accompanying drawings, in which:

Figure 1 is a view in side elevation, part being shown in section, of a portion of an escalator hand rail constructed in accordance with the present invention;

Figure 2 is a sectional view taken along line 2—2 of Figure 1;

Figure 3 is a perspective view of a connector of the form shown in Figures 1 and 2;

Figure 4 is a view corresponding to Figure 1 and showing another embodiment of the invention; and

Figure 5 is a sectional view taken along line 5—5 of Figure 4.

In accordance with the present invention, an escalator hand rail is composed of a plurality of short sections of helically coiled wire assembled end-to-end and ultimately joined to form an endless loop, as shown in my copending application Serial No. 663,222 filed concurrently herewith. The junctions between the successive sections of coiled wire are accomplished by utilizing the interior contour of the coil of wire as a screw thread, and providing an exteriorly threaded member for screw thread engagement with the last turn or two of the section of coiled wire on both sides of the junction. If it is desired to drive the hand rail by an auxiliary means, such as an endless chain, provision may be made for interconnecting the drive chain with one or more of the externally threaded connecting members.

Referring now to Figure 1 of the drawings, a section 1 of helically coiled wire, having an endmost turn 2, is connected to the adjacent endmost turn 3 of another section of helically coiled wire 4. The connection is accomplished by a ring 5, whose exterior contour is screw threaded, as shown at 6, for complementary engagement with the interior of the last turn or two of the coiled sections 1 and 4.

The sections of helically coiled wire 1 and 4 are duplicates of each other and the duplication is repeated throughout the entire length of an endless loop, which constitutes a continuous hand rail. The various turns of the several sections of

2

coiled wire are preferably wound to the same pitch and the wire is preferably of uniform cross section, so as to provide a coil-spring-like member having closely compacted turns with a relatively smooth exterior and uniform pitch. The external thread formations on ring 5 are of the same pitch and complementary in contour to the interior configurations of the endmost turns of each of sections 1 and 4 and their duplicates. 10 The ring 5 is provided with an aperture 7, through which extends the stem of a saddle member 8. The stem of saddle member 8 within ring 5 may be secured by a suitable nut, or by riveting, and the lower extremity of saddle member 8 is pivotally connected by a pin 9 to each of the side links 10 of an endless roller chain 11.

At the end of coil section 1, opposite endmost turn 2, the connector 5 and saddle member 8 are duplicated to connect the endmost turn 12 of section 1 with the endmost turn 13 of next succeeding coiled section 14.

Referring now particularly to Figure 2, it will be observed that the end of turn 13 abuts the stem of saddle member 8 on one side and that the end 25 of turn 12 abuts the stem of saddle member 8 on the other side. The adjacent ends of turns 12 and 13, therefore, lie in the same threaded groove of ring 5 and the connection between sections 1 and 14, as between sections 1 and 4 and all other comparable sections, is accomplished without discontinuity in the external appearance of the hand rail.

As clearly shown in Figure 2, the pins 9 may be extended laterally to ride in channels 15 and 16 arranged, respectively, in stationary guide rails 17 and 18, thereby confining the orbit of chain 11 and concomitantly defining the orbit of the hand rail composed of sections 1, 4, 14, and their duplicates, throughout the endless loop.

40 Referring now particularly to Figures 4 and 5 for a modified form of the invention, which is adaptable particularly to conditions in which it is desired to use longer sections of coiled wire, i. e., fewer sections per given length of loop than 45 in the embodiment just described, two sections of coil 21 and 22, having endmost turns 23 and 24, respectively, are threaded upon a ring 25, whose exterior is provided with thread formations 26 corresponding in pitch and configuration to the interior of the endmost turn or two of sections 21 and 22. In this embodiment, the ring 25 is provided with an integral stem 27 extending radially therefrom and terminating in a head 28, to which is secured, as by welding or riveting, 50 a pair of flanges 29 and 30, which may, and as

shown in Figure 4 do, constitute the outside links of the drive chain 31 at that point. In this form, the connecting pins 32 at each end of flange members 29 and 30 are extended laterally to receive the guide rollers 33, which latter engage a suitable track 34 arranged within a stationary rail 35. In this embodiment, as in the previous embodiment, the ends of the endmost turns 23 and 25 lie in the same threaded groove in ring 25 and approximately abut stem 27, as clearly shown in Figure 4.

In order to permit the use of relatively long sections of coiled wire without permitting increments thereof to substantially deviate from the orbit of the driving and guiding chain, the coil sections, such as 21, may be joined to the driving chain intermediate the ends of the sections, as shown at the right side of Figure 4. At this point, a hole 42 is drilled through contiguous turns 43 and 44 of coil section 21, part of the hole 42 being in one turn and part thereof in another. Adjacent the hole 42, the drive chain 31 is again provided with flanged members 29 and 30, across which is a bridge member 45 having an opening 46 in alignment with hole 42. Extending through hole 42 and opening 46 is a rivet 47, preferably of the externally applied type. This type of connection may be repeated as often as necessary between the ends of any given coil section, such as 21, it being understood that the type of connection shown at 42 is primarily intended to maintain the orbit of the spring section 21 in conformity with the orbit of the drive chain 31, while such pull as is exerted upon the endless loop of hand rail, consisting of the series of coiled spring sections, is transmitted through connecting rings like 25.

From the foregoing description, those skilled in the art will understand that the present invention accomplishes its objects and provides an escalator hand rail which is easy and economical to fabricate, adaptable to a variety of uses, and which lends itself to repair by replacement of sections without requiring a replacement of the entire hand rail, should a rupture occur. With the threaded interconnection of the respective sections of coiled wire, it is not possible for the respective sections to work loose while in operation because the direction of turn to connect them together is uniform throughout and relative radial movement of the connecting members is precluded by the fact that all are connected to the drive chain.

While two forms of the invention have been disclosed in detail, it is readily apparent that

many modifications and variations will present themselves to those skilled in the art without departing from the spirit of the invention, and consequently it is to be understood that the invention is not limited to the details described.

Having thus described the invention, what is claimed and desired to be secured by Letters Patent is:

1. A hand rail for an escalator comprising a plurality of short sections of helically coiled wire, rings having external threads of the same pitch as and complementary contour to the terminal turns of said sections, said rings having a stem projecting radially outward to interrupt said external threads substantially centrally thereof, said sections being screwed upon said rings until an end of the former is adjacent the radial stem of the latter, and driving means connected to the stem of said rings.

2. A hand rail for an escalator comprising an endless loop of elongatable material constituting the exposed grip member, an endless loop of substantially unelongatable material constituting the drive member, said grip member being peripherally longer than said drive member, and connections at intervals along the length of said grip member and said drive member, said connections maintaining said members in the same spaced relation and in vertical alignment with each other throughout the orbits of said members.

3. A hand rail for an escalator comprising a plurality of short sections of helically coiled wire, connectors joining said sections in end-to-end relation to form a loop, some of said connectors each having a stem projecting therefrom beyond the periphery of said sections, and an endless driving chain arranged within the inner periphery of said loop, said stems being connected respectively with spaced links of the chain, and maintaining said loop and said chain in vertical alignment.
